(57) **CLAIM**

The ornamental design for a suspended luminaire, as shown and described.

DESCRIPTION

1. Suspended luminaire

Figures 1.1 to 1.7 show different views of a suspended luminaire.

Figure 1.1 shows a perspective view of the suspended luminaire.

Figure 1.2 shows a front view of the suspended luminaire.

Figure 1.3 shows a rear view of the suspended luminaire.

Figure 1.4 shows a left side view of the suspended luminaire.

Figure 1.5 shows a right side view of the suspended luminaire.

Figure 1.6 shows a bottom view of the suspended luminaire.

Figure 1.7 shows a top view of the suspended luminaire.

1 Claim, 7 Drawing Sheets
